UNITED STATES PATENT OFFICE

2,040,791

LOOM HARNESS

John Jacob Kaufmann, Elkins Park, Pa., assignor to Steel Heddle Manufacturing Company, Philadelphia, Pa., a corporation of Pennsylvania

Application January 4, 1935, Serial No. 369

11 Claims. (CL. 139—52)

This invention relates to loom harness, and relates more particularly to that type of harness which is used for cross or doup weaving, in which the warp threads arranged in pairs are crossed or 5 twisted about each other, although it should be understood that certain portions of the present invention are also applicable to other types of loom harness.

The principal object of the present invention is 10 to provide simple and efficient metallic harness for cross weaving, in which each of the lifting heddles will be made of a single strip of metal, whereby crowding of the harness will be eliminated.

15 A further object of the invention is to provide metallic harness for cross weaving by means of which greater freedom of the warp will be obtained in the shedding, and in the use of which likelihood of the warp ends fouling on each other 20 and on the doup needle will be greatly minimized, so that there will be fewer faults in the fabrics woven by means of the harness.

25 A further object of the invention is to provide an improved construction of heddles which will serve to prevent nesting or interlocking of certain parts of each heddle with adjacent heddles in a series, which objectionable nesting is likely to cause certain of the heddles to be elevated when not desired, resulting in misweaves and errors in 30 the pattern of the material being woven.

The nature and characteristic features of the 35 invention will be more readily understood from the following description, taken in connection with the accompanying drawing forming part hereof, in which:

Figure 1 is a vertical elevation of one set of elements for controlling a pair of warp ends in cross weaving, said elements being shown detached from the harness frames in which they 40 are customarily mounted;

Fig. 2 is an enlarged detail view of the central portion of the same;

Fig. 3 is an edge view of the central portion of one of the guide or lifting heddles shown in 45 Fig. 2;

Fig. 4 is an enlarged horizontal section of one of the lifting heddles, the section being taken approximately on line 4—4 of Fig. 1;

Fig. 5 is a similar view, the section being taken 50 approximately on line 5—5 of Fig. 1;

Fig. 6 is an enlarged elevational view of the central or eye portion of a heddle which may be used for controlling a warp end in plain weaving, or for controlling the pile wire of pile fabric looms 55 in which longitudinal pile wires are used, the

same as shown embodying one of the principal novel features of the present invention;

Fig. 7 is a side elevation of the structure shown in Fig. 6; and

Fig. 8 is a rear elevation thereof.

It will, of course, be understood that the description and drawing herein contained are illustrative merely, and that various modifications and changes may be made in the structure disclosed without departing from the spirit of the 10 invention.

Referring now more particularly to Figs. 1 to 5 of the drawing, there is there shown an arrangement of a pair of lifting heddles 10, and a doup needle 11 used therewith, all of the same general 15 type as those shown in my previous Letters Patent No. 1,037,150, dated October 27, 1912, and used for doup or cross weaving.

In the present instance, the lifting heddles 10 are made from a thin, flat strip of metal, each 20 having an angularly extending portion 12, whereby by the upper part 13 of the heddle is offset laterally with respect to the lower part 14 thereof, to afford freedom of action of the doup needle 11 when it is selectively raised by one or the other of 25 the lifting heddles 10.

A central strip 15 of the eye portion of the lifting heddle 10 is punched out of the main plane of the remaining parts of the heddle (see Figs. 2 and 4), thereby permitting the eye portion of the 30 doup needle 11 to be disposed in the eye provided between said punched out strip 15 and the side strips 16 of the heddle, without distorting said doup needle, which is also preferably punched from flat metal. The side strips 16 are also preferably punched out of the main plane of the 35 heddle.

The lower portions of the punched out strip 15 and of the side strips 16 lie in separated planes for the accommodation of the eye portion of the 40 doup needle 11, whereas the upper portions of said strips 15 and 16 preferably blend into the main plane of the upper portion 13 of the heddle in a gradual slope, thereby avoiding any definite hump at the upper part of the eye portion of the 45 heddle, which would interfere with the smooth passage of the warp ends when the shedding takes place.

The central strip 15, as well as the side strips 16, follow the contour of the bend or offset 12 in the 50 eye portion of the heddle. These strips ordinarily extend from a point in the lower straight portion 14 of the heddle, below the bend or offset 12, to a point in the upper straight portion 13 of the heddle, some distance above the bend 12. Near 55

the lower end of the punched out strip 15, said strip is spread laterally, as at 17, by swaging or other suitable operation, whereby there are provided overhanging portions resulting in a width 5 of the punched out strip 15 at this point which is greater than that of the slot from which said strip 15 was originally punched. This spreading of the punched out strip 15 at this point may be readily accomplished by means of a suitable swaging operation in the heddle making machine. Being provided near the lower end of each strip 15, the laterally spread portions 17 will be most effectively located, when the punched out strips are of considerable longitudinal extent, to prevent nesting 10 of the central strips 15 in the slots of adjacent heddles.

When the guide or lifting heddles 10 of a set of doup elements are constructed as aforesaid, the side strips 16 of the central portion of each lifting 20 heddle will, when the warp ends are arranged as in Fig. 2, serve to guide the ground end over the doup end and over the upper end of the doup needle. When, however, the warp ends are entered otherwise, as is sometimes required in certain 25 types of fancy weaving, then the swaged portion 17, where the central strip 15 is spread laterally, will effectively serve this purpose.

It should here be noted that, by reason of the doup heddle 10 at one side of each set being turned 30 about, on its vertical axis, with respect to the other doup heddle 10 of the set, there will be no necessity to provide right and left hand heddles, notwithstanding that the heddles are offset at the central portions thereof, as hereinbefore set forth.

35 That portion of the invention which relates to the spreading of a part of the punched out strip 15 of a heddle, to prevent nesting of the heddle with adjacent heddles in a series, is equally applicable to other types of heddles. For example, in Figs. 6, 7, and 8 of the drawing there is shown an arrangement provided where the punched out central strip 15^a of the heddle 10^a is of considerably less longitudinal extent than is the case where the invention is applied to cross weaving 45 harness, as shown in Figs. 1 to 5. The structure shown in Figs. 6, 7, and 8 is suitable for the eye portions of heddles for controlling warp ends in plain weaving, or for controlling longitudinal pile wires in pile fabric looms such as are used for 50 weaving pluses, velvets, friezes, etc.

In this instance, the central portion of the punched out strip 15^a is spread laterally, as at 17^a, in order to provide overhanging portions which prevent the entrance of the punched out portion 55 15^a of the heddle 10^a into the slot between the two side strips 16^a of the eye portion of an adjacent heddle.

Loom harness elements constructed as herein described can be readily made at no extra expense 60 in the heddle making machines which are now used for making heddles from thin, flat strips of metal, and when so constructed will serve to prevent nesting of the heddles not only when the same are mounted in the loom, but also during their 65 manufacture, it being well known that when such nesting occurs during the making of the heddles certain of the operations are seriously interfered with.

I claim:

70 1. In a loom harness for cross weaving, a pair of lifting heddles each comprising a single thin flat strip of metal having an eye portion formed of a plurality of strips disposed in several planes, and a doup needle having its eye portion engaged 75 by the eye portion of each of the lifting heddles,

the eye portion of each lifting heddle having an angularly extending part whereby the upper part of said heddle is offset laterally with respect to the lower part thereof, and the strips forming said eye portion following the contour of said 5 offset.

2. In a loom harness for cross weaving, a pair of lifting heddles each comprising a single thin flat strip of metal having an eye portion formed of a plurality of strips disposed in several planes, 10 and a doup needle having its eye portion engaged by the eye portion of each of the lifting heddles, the eye portion of each lifting heddle having an angularly extending part whereby the upper part of said heddle is offset laterally with respect to 15 the lower part thereof, and the strips forming said eye portion following the contour of said offset and extending above and below the same.

3. In a loom harness for cross weaving, a pair of lifting heddles each comprising a single thin 20 flat strip of metal having an eye portion formed of a plurality of strips disposed in several planes, and a doup needle having its eye portion engaged by the eye portion of each of the lifting heddles, the eye portion of each lifting heddle having an 25 angularly extending part whereby the upper part of said heddle is offset laterally with respect to the lower part thereof, the strips forming said eye portion following the contour of said offset and extending above and below the same, and the 30 lower end of one strip of the eye portion of each heddle having a portion extending laterally to prevent nesting of said eye portion with the eye portion of a similar and adjacent heddle.

4. In a loom harness for cross weaving, a pair 35 of lifting heddles each comprising a single thin flat strip of metal having an eye portion formed of a central strip and two side strips, the central strip being disposed out of the plane of the side strips, and a doup needle having its eye portion 40 engaged by the eye portion of each of the lifting heddles, the eye portion of each lifting heddle having an offset, the strips forming said eye portion following the contour of said offset and extending above and below the same, and 45 the lower end of the central strip of the eye portion of each heddle having a portion extending laterally to prevent nesting of said eye portion with the eye portion of a similar and adjacent heddle. 50

5. In a loom harness for cross weaving, a pair of lifting heddles each comprising a single thin flat strip of metal having an eye portion formed of a central strip and two side strips, the central strip being disposed out of the plane of the side 55 strips, and a doup needle having its eye portion engaged by the eye portion of each of the lifting heddles, the eye portion of each lifting heddle having an offset, the strips forming said eye portion following the contour of said offset and extending above and below the same, each of the lifting heddles being of similar shape and one being turned with respect to the other on its vertical axis, and the lower end of the central strip of the eye portion of each heddle having a portion 60 extending laterally to prevent nesting of said eye portion with the eye portion of a similar and adjacent heddle. 65

6. In a loom harness, a heddle comprising a thin 70 flat strip of metal having an eye portion formed of three strips, one of said strips being disposed in a different plane from that of the other strips, and one of said strips having a portion extending laterally to prevent nesting of the eye por- 75

tion with the eye portion of a similar and adjacent heddle.

7. In a loom harness, a heddle comprising a thin flat strip of metal having an eye portion formed of three strips and having a slot between two of said strips, one of said strips having a portion extending laterally to prevent nesting of the eye portion with the eye portion of a similar and adjacent heddle.

8. In a loom harness, a heddle comprising a thin flat strip of metal having an eye portion formed of two side strips having a slot between the same and a central strip disposed in a different plane from that of the side strips, one of said strips having a portion extending laterally to prevent nesting of said central strip in the slot of a similar and adjacent heddle.

9. In a loom harness, a heddle comprising a thin flat strip of metal having an eye portion formed of two side strips having a slot between the same and a central strip disposed in a different plane from that of the side strips, said central strip hav-

ing a portion extending laterally to prevent nesting of said central strip in the slot of a similar and adjacent heddle.

10. In a loom harness, a heddle comprising a thin flat strip of metal having an elongated eye portion formed of two side strips having a slot between the same and a central strip disposed in a different plane from that of the side strips, said central strip having a portion near one end thereof extending laterally to prevent nesting 10 of said central strip in the slot of a similar and adjacent heddle.

11. In a loom harness, a heddle comprising a thin flat strip of metal having an eye portion formed of two side strips having a slot between 15 the same and a central strip disposed in a different plane from that of the side strips, said central strip having a laterally expanded portion to prevent nesting of said central strip in the slot of a similar and adjacent heddle. 20

JOHN JACOB KAUFMANN.
